MERCANDISE CARTON

Raymond E. Fink, Foxon, Conn., assignor, by
mesne assignments, to National Folding Box
Company, Incorporated, a corporation of Con-
necticut

Application May 30, 1944, Serial No. 537,985

14 Claims. (Cl. 229—6)

1

This invention relates to merchandise cartons, and more particularly to an improved carton folder adapted to be folded and wrapped around an article of merchandise to provide an economical and sturdy carton therefor.

In accordance with this invention, the carton folder comprises essentially enclosing panels which are wrapped around the articles of merchandise to provide an enclosed tube within which the merchandise article is contained. The enclosing panels may, for convenience, be designated as comprising a front wall panel, a bottom wall panel, a rear wall panel and a closure panel or flap hingedly connected along score lines extending longitudinally of the carton. An end wall panel is provided at each end of the tubular body which when assembled is inset within the tubular body. Each end wall panel is hingedly connected to the adjacent end of the bottom wall panel by a spacer section, which is folded to overlie the inside face of the bottom wall panel. The front edge of each end wall panel is connected to the adjacent end of the front wall panel by a bellows fold portion designed to overlie the inside face of the front wall panel. Similarly, the rear edge of each end wall panel is connected to the adjacent end of the rear wall panel by a bellows fold portion which overlies the inside face of the rear wall panel. Each bellows fold portion comprises a pair of collapsing sections which fold one upon the other when the folder is assembled into carton form. Thus each end wall panel is rigidly maintained in fixed position within the tubular body by the end spacer section, and a pair of bellows fold sections.

Where a carton having four sides is to be formed, the enclosing panels comprise bottom, rear and front wall panels and a closure panel which fold around the end wall panels which have four corresponding sides. An out-turned bracer flap may be hinged to the top edge of each end wall panel, the bracer flaps bracing and providing a support for the closure panel. Each bracer flap may also be provided with a pair of locking tabs which may be inserted between the adjacent front and rear wall panels and the adjacent bellows fold portions to thereby maintain the front and rear wall panels in rigid carton assembled position prior to closing of the cover panel.

Cartons may be formed in accordance with this invention having any desired shape or cross-sectional contour. For example, in place of a four-sided carton, a carton having only three sides, in which the enclosing panels comprise only the bottom, front and rear wall panels, which are wrapped around corresponding triangular shaped end wall panels. In the case of triangular shaped carton, the rear wall panel may be provided with a tuck-in flap which is hinged thereto and which

2

may be inserted between the inside face of the front wall panel and the adjacent bellows fold portions, thereby retaining the carton in closed assembled form.

5 Cartons formed in accordance with this invention may be used to contain numerous articles of merchandise which can be placed upon the bottom wall panel of the blank or wrapper and the wrapper then assembled into carton form around the article. In assembling the wrapper the end portions of the blank or wrapper are folded over the bottom wall panel. When the end panels are raised to a position substantially at right angles to the bottom wall panel, the front and rear wall panels will automatically swing into erect carton forming position. The wrapper may also be assembled around the merchandise by folding the end portions of the blank inwardly and then raising the front and rear wall panels into erect container form position, which operation will automatically raise and retain the end wall panels in erect container forming position. The article becomes completely enclosed within the carton when the cover panel is swung into closed position and its tuck-in flap inserted between the inside face of the front wall panel and the adjacent bellows fold sections; or, if the carton has three sides and had no cover panel, the tuck-in flap hinged to the rear wall panel is inserted between the inside face of the front wall panel and the adjacent bellows fold portions.

35 Where the carton is to contain articles of relatively fragile nature that should be suspended within the carton in spaced relation to the enclosing panels, suitable apertures or other means are associated with the end wall panels which permits suspension of the article by and between the end wall panels in spaced relation to the enclosing panels. The ends of the article are further protected from damage or injury by the ends of the enclosing panels which extend beyond the end wall panels to form a protecting rim at each end of the carton.

40 It will be noted that no glueing or other machine operations are required to assemble the folder, and therefore relatively unskilled labor may be used to simultaneously package the article and assemble the folder into carton form. The in-turned end spacer section, and in-turned bellows fold portions reinforce and strengthen the bottom wall panel and the front and rear wall panels, while the out-turned bracer flap strengthens, reinforces and provides a support for the cover panel when in closed position.

55 The carton folders may be economically cut and scored in multiple from large sheets or rolls of fiberboard, box board and like paperboard material on an automatic cutting and scoring machine. The sheets or rolls need be imprinted on one side only, since only one side of the wrap-

per is exposed as the outside face of the formed carton.

An object of this invention is to provide an improved folder which may be formed from a single blank of paperboard material, and which may be folded to enclose an article of merchandise and provide a protective carton therefor which requires no glueing or machine operation in its assembly.

Another object of this invention is to provide a sturdy and economical carton particularly designed for the packaging of delicate and fragile articles and which may be formed from a prepared blank without machine assembly.

Other objects of this invention will become apparent as the disclosure proceeds.

Although the characteristic features of this invention are believed to be novel as particularly pointed out in the claims appended hereto, the invention itself, as to its objects and advantages and the manner in which it may be carried out, may be better understood by referring to the following description taken in connection with the accompanying drawings forming a part hereof, in which:

Fig. 1 is a plan view of the inside face of a prepared blank which forms the carton folder;

Fig. 2 is a perspective view of the folder blank shown in Fig. 1 as it appears at one stage of assembly into carton form;

Fig. 3 is a perspective view of the folder as it appears when erected in carton form with the cover panel in open position;

Fig. 4 is a perspective view of the fully assembled carton with the cover panel in closed position;

Fig. 5 is a longitudinal cross-sectional view of the carton as it appears when viewed along line 5—5 of Fig. 4;

Fig. 6 is an inside face view of a prepared blank which forms a carton folder provided with locking tabs for maintaining the box forming part of the carton in erect position;

Fig. 7 is a perspective view of the folder shown in Fig. 6 as it appears at one stage of assembly into carton form;

Fig. 8 is a perspective view of the same folder as it appears at a further stage of assembly into carton form;

Fig. 9 is a perspective view of the carton showing the box part thereof fully assembled and maintained in an erect position by the locking tabs, the cover panel being shown in open position;

Fig. 10 is a horizontal cross-sectional view of the fully assembled and closed carton;

Fig. 11 is a transverse cross-sectional view through the fully assembled carton as appears when viewed along line 11—11 of Fig. 10;

Fig. 12 is a plan view of the inside face of a prepared blank which forms a carton folder of generally triangular cross-section;

Fig. 13 is a perspective view of the folder blank shown in Fig. 12 as it appears at one stage of assembly into a triangular shaped carton;

Fig. 14 is a perspective view of the folder as it appears when erected in carton form and prior to final insertion of the tuck-in flap;

Fig. 15 is a perspective view of the fully assembled triangular shaped carton in closed position; and

Fig. 16 is a transverse cross-sectional view through the triangular shaped carton as it appears when viewed along line 16—16 of Fig. 15.

Similar reference characters refer to similar

parts throughout the several views of the drawings and specification.

The folder forming blanks shown in Figs. 1 and 12 may be formed from paperboard material of suitable quality cut and scored to provide a one-piece folder adapted to be quickly and conveniently erected into carton form. The blanks as shown in Figs. 1 and 12 may be economically formed on a cutting and creasing machine adapted to cut and crease the blanks in multiple interfitted arrangement from large sheets or rolls of the selected paperboard material.

The prepared blank shown in Fig. 1 comprises a bottom wall panel 1, a front wall panel 2 hinged to the bottom wall panel 1 along a score line 4, and a rear wall panel 3 hinged to the opposite edge of the bottom wall panel 1 along the score line 5. A cover panel 6 is hinged to the opposite edge of the rear wall panel 3 along a score line 7. The cover panel 6 may be provided with a tuck-in flap 8 hinged to the front edge thereof along score line 9.

An end wall panel 14 is provided at each end of the blank, each of which is connected to the adjacent end of the bottom panel wall 1 by an end spacer section 10. The end spacer section 10 is hinged to the adjacent end of the bottom wall panel 1 by a score line 11 extending substantially at right angles to the score lines 4 and 5. The associated end wall panel 14 is hinged to the end spacer section 10 by a score line 15 which extends substantially parallel to the score line 11. The end wall panels 14 are of such size and shape as to snugly seat between the front wall panel 2 and rear wall panel 3 when the box-forming part of the carton is erected into container forming position, and the end spacer sections when folded over the inside face of the bottom wall panel 1 maintain the end wall panels in final inset position, as shown more particularly in Fig. 2.

The front edge of each end wall panel 14 is joined to the adjacent end of the front wall panel 2 by means of a bellows fold portion comprising hingedly connected bellows sections 12 and 16. Each bellows section 12 is hingedly connected to the adjacent edge of the front wall panel 2 by a score line 11', which is substantially in alignment with and a continuation of the score line 11. The companion bellows fold panel 16 is hinged to the front edge of the adjacent end wall panel 14 along the score line 23'. A diagonal extending score line 18 provides a hinging connection between the bellows sections 12 and 16. The score line 18 substantially meets the score lines 23' and 15 at their point of intersection. Bellows section 12 is separated from end spacer section 10 by a cut-line 4' which is substantially in alignment with the score line 4.

The rear side edge of each end wall panel 14 is similarly connected to the adjacent end of the rear wall panel 3 by a bellows portion which comprises a pair of bellows sections 13 and 17 hingedly connected along the diagonally extending score line 19. Bellows section 13 is hinged to the end of rear wall panel 3 along the score line 11'' which extends substantially in alignment with the score line 11, and bellows section 17 is hingedly connected to the rear side edge of end wall panel 14 along score line 23. A cut line 5' separates bellows section 13 from the adjacent end spacer section 10, cut line 5' being substantially in alignment with score line 5. The diagonally extending score line 19 provides a hinging connection between the bellows sections 13 and 17 at the point

of intersection of the score line 15 with score line 23.

A bracer flap 20 is hingedly connected to the upper edge of each end wall panel 14 by a score line 21. Each of the end wall panels 14 may be provided with a suitable opening 22 designed to receive and thereby support the article to be packed in the carton. The blanks which have been cut to the form shown in Fig. 1 may be shipped to the merchandise packer in flat condition to be thereafter set up and folded to contain the merchandise as needed.

The blank as shown in Fig. 1 may be quickly assembled into carton form by a few simple, quickly performed operations. Each end portion of the blank is folded about the score lines 11', 11 and 11" so that bellows section 12 will overlie the inside face of front wall panel 2, end spacer section 10 will overlie the inside face of bottom wall panel 1, and bellows section 13 will overlie the inside face of rear wall panel 3, as illustrated in Fig. 2. By raising the front wall panel 2 and rear wall panel 3 into a position substantially at right angles to the bottom wall panel 1, the end wall panels 4 will be automatically erected into a position substantially at right angles to the bottom panel wall 1. Or, as an alternative method of assembly, the end wall panels 14 may be raised to a position substantially at right angles to the bottom wall panel 1, and this operation will automatically raise the front wall panel 2 and the rear wall panel 3 into a position substantially at right angles to the bottom wall panel 1, and thus erect the carton into container form. By either method of assembly bellows fold sections 12 will hug the inside face of front wall panel 2 and bellows sections 13 will hug the inside face of rear wall panel 3, bellows sections 16 automatically folding to overlie their companion bellows sections 12 and bellows sections 17 automatically folding to overlie their respective companion section 13. Prior to or during this manipulation of the front wall panel 2 and the rear wall panel 3, the merchandise article "T" may be inserted into position.

Upon erection of the box part comprising bottom wall panel 1, front wall panel 2, rear wall panel 3 and end wall panels 14 into merchandise-containing position, the carton will appear as illustrated in Fig. 3, the bracer flaps 20 are outwardly turned to provide a strut extending between the front and rear wall panels and a support for the end wall panels. The carton is closed by swinging the cover panel 6 into a closed position so as to overlie the bracer flaps 20, and the tuck-in flap 8 may be inserted between the inside face of the front wall panel 2 and the adjacent bellows sections 12, as indicated in Fig. 4. The cover parts may be maintained in this closed position by the provision of a sealing strip 30 adhesively secured to the cover panel 6 and the front wall panel 2 so as to extend over the front edge of the closed carton as shown in Fig. 4, or if desired staples 31 or similar securing means may be provided at each end of the box, which secure the front wall panel 2 to the tuck-in flap 8 and the adjacent bellows section 12.

There is shown in Fig. 6 a prepared paperboard blank which is similar to the blank shown in Fig. 1 except for the addition of locking tabs 24 and 25 associated with each of the bracer flaps 20. The locking flap 24 is hinged to a side edge of the bracer flap 20 along the score line 26, which substantially meets the end of the score line 23' and a locking flap 25 is hinged to the

opposite side edge of each bracer flap 20 along the score line 27 which substantially meets the end of the score line 23, as illustrated in Fig. 6.

The blank as shown in Fig. 6 is folded into carton form by first folding end portions about the score line 11', 11 and 11", in the manner heretofore described, so that bellows section 12 overlies the inside face of the front wall panel 2, and bellows section 13 overlies the inside face of rear wall panel 3. The end wall panels 14 may then be raised, and the article "T" inserted into position. Raising of the end wall panels 14 automatically raises the front and rear wall panels into erect position. The bracer flaps 20 are then folded outwardly as shown in Fig. 8 and the locking tabs 24 inserted between the inside face of the front wall panel 2 and adjacent face of the bellows section 12, and similarly the locking tabs 25 are inserted between the inside face of the rear wall panel 3 and the adjacent face of the bellows section 13. The locking tabs 24 and 25 may have a rounded edge 26' if desired to facilitate insertion. It will be noted by referring to Fig. 9 that the locking tabs 24 and 25 maintain the front wall panel 2 and the rear wall panel 3 in rigid box assembled position to provide a set up box part which is held in rigid set up position prior to closing of the cover panel 6. The cover panel 6 is swung into closed position so as to overlie the bracer flaps 20 and the cover tuck-in flap 8 may be inserted between the inside face of the front wall panel 2 and the outside face of the adjacent locking tabs 24 to hold the cover panel in closed position, as shown in Fig. 11. The cover panel may be sealed in closed position by means of an adhesive strip 30 or by means of staples 31, as illustrated in Fig. 4.

There is illustrated in Fig. 12 a prepared blank 40 or wrapper designed to form a carton presenting only three enclosing panels and illustrating that various other carton shapes may be formed by employing the teachings of this invention. The blank as shown in Fig. 12 comprises a bottom 45 wall panel 1, front wall panel 2 hinged to the bottom wall panel 1 along the score line 4, a rear wall panel 3 hinged to the opposite edge of the bottom wall panel 1 along the score line 5 and a tuck-in flap 8 hinged to the top edge of the 50 rear wall panel 3 along a score line 9'. The triangular end wall panel 14' at each end of the blank is connected to the adjacent end of the bottom wall panel 1 by an end spacer section 10, the end spacer section 10 being hinged to the 55 adjacent end of the bottom wall panel 1 by a score line 11 extending substantially at right angles to the score lines 4 and 5. Each end wall panel 14' is hinged to the end spacer section 10 by a score line 15 which extends substantially 60 parallel to the score line 11.

The front edge of each end wall panel 14' is joined to the adjacent end of the front wall panel 2 by means of a bellows fold portion comprising hingedly connected bellows sections 12 and 16'. 65 Each bellows section 12 is hingedly connected to the adjacent edge of the front wall panel 2 by a score line 11' which is substantially a continuation of the score line 11. The companion bellows fold panel 16' is hinged to the front edge of the 70 triangular end wall panel 14' along the edge forming score line 31. A diagonally extending score line 18 provides a hinging connection between the bellows section 12 and 16' and substantially meets the score lines 31 and 15 at their 75 point of intersection. Bellows section 12 is

separated from end spacer section 10 by a cut line 4' which is substantially in alignment with score line 4.

The rear side edge of each triangular wall panel 14' is similarly connected to the adjacent end of the rear wall panel 3 by a bellows fold portion which comprises a pair of bellows sections 13 and 17' hingedly connected along the diagonally extending score line 19. Bellows section 13 is hinged to the end of rear wall panel 3 along the score line 11'', which is substantially a continuation of score line 11, and bellows section 17' is hingedly connected along the edge forming score line 32 to the adjacent end wall panel 14'. A cut line 5' separates bellows section 13 from the adjacent end spacer section 10, cut line 5' being substantially in alignment with score line 5.

The blank shown in Fig. 12 may be quickly assembled by folding each end portion of the blank about score lines 11', 11 and 11'' so that bellows section 12 will overlie the inside face of front wall panel 2, end spacer section 10 will overlie the inside face of bottom wall panel 4, and bellows section 13 will overlie the inside face of rear wall panel 3, as illustrated in Fig. 13. By raising the triangular end wall panel 14' to a position substantially at right angles to the bottom wall panel 4, the front and rear wall panels 2 and 3 will be raised to the position shown in Fig. 13. The contents or merchandise can be placed upon the bottom wall panel 4 and the front and rear wall panels 2 and 3 further raised to the position shown in Fig. 14. The tuck-in flap 8 may then be inserted between the inside face of the front wall panel 2 and the adjacent face of the bellows sections 12 to lock the carton in fixed assembled form. If desired, suitable apertures or other means may be associated with the end wall panels 14' to provide suspension means for the article contained therein.

From the above description, it is evident that a carton folder has been provided which may be economically formed from a single blank of pasteboard, fiberboard or other like paperboard material, which need be printed on one side only thereof and may be cut and creased in multiple interfitted arrangement at high production speeds on an automatic cutting and creasing machine. Since only one side of the blank forms the outside exposed face of the finished carton, only the outside face of the blank need be calendered or otherwise finished and imprinted. The blanks may be stacked flat in limited space and thus economically shipped to and stored by the merchandise packer. Each blank is set up in carton form by a simple wrapping operation wherein the merchandise article is wrapped within the folder and packaged therein as the folder is set up.

No adhesive or other securing means is required in assembling the folder into carton form and no glueing or box assembly machinery is needed by the merchandise packer to assemble and close the carton.

The assembled carton is rigid and strong in construction. If the contained article "T" is delicate or subject to injury, it may be held suspended between the inset end wall panels and the ends of the article are thus adequately protected by the projecting ends of the enclosing panels. The enclosing panels, when fully assembled in carton form, are spaced from the article "T," as shown in Figs. 5 and 10, so that any blows which these enclosing panels may encounter are not delivered to the article "T" contained within

the carton. The assembled carton body is also protected, strengthened and reenforced by the end spacer section 10, and the bellows sections 12 and 13. Out-turned bracer flaps 20 may be provided as reinforcing support for the cover panel 6, assist in maintaining the enclosing panels 2 and 3 in spaced relation, and further serve to stiffen and strengthen the end wall panels 14, with which they are associated. This improved carton provides a highly convenient and economical medium for packaging numerous articles of merchandise, including fragile articles such as radio tubes, vacuum tubes, electric and fluorescent light bulbs and tubes, glassware, delicate instruments, and the like, which should be protectively suspended within the carton.

While certain novel features of the invention have been disclosed and are pointed out in the annexed claims, it will be understood that various omissions, substitutions and changes may be made by those skilled in the art without departing from the spirit of the invention.

What is claimed is:

1. An improved carton folder comprising enclosing panels providing a tubular body, and an end closure for said tubular body comprising an end wall panel in-set within the tubular body and hingedly connected to two of said enclosing panels by bellows fold portions, each of said bellows fold portions comprising a main bellows section and a complementary bellows section, each of said main bellows sections being hinged to the adjacent end of the adjacent enclosing panel and adapted to overlie the inside face thereof, said main bellows section presenting an outer part extending from the end of the enclosing panel section to the plane of the erected end wall panel and an inner section extending inwardly beyond the plane of the erected end wall panel, said complementary bellows section being hinged to the inner end of said main bellows section and to the adjacent side edge of the end wall panel and adapted to overlie only the inner part of said main bellows section when the end wall panel is in erect position.

2. An improved carton folder comprising enclosing panels providing a tubular body, a pair of spaced end wall panels in-set within the tubular body, and a pair of bellows fold portions connecting each end wall panel to the adjacent enclosing panels, each of said bellows fold portions comprising a main bellows section and a complementary bellows section, each of said main bellows sections being hinged to the adjacent end of the adjacent enclosing panel and adapted to overlie the inside face thereof, said main bellows section presenting an outer part extending from the end of the enclosing panel section to the plane of the erected end wall panel and an inner section extending inwardly beyond the plane of the erected end wall panel, said complementary bellows section being hinged to the inner end of said main bellows section and to the adjacent side edge of the end wall panel and adapted to overlie only the inner part of said main bellows section when the end wall panel is in erect position.

3. An improved carton folder having a bottom wall panel, a front enclosing panel and a rear enclosing panel, a pair of spaced end wall panels adapted to seat between said front and rear enclosing panels, and a pair of bellows fold portions hingedly connecting each end wall panel to the adjacent ends of said front and rear enclosing panels, each of said bellows fold portions comprising a main bellows section and a complementary

bellows section, each of said main bellows sections being hinged to the adjacent end of the adjacent enclosing panel and adapted to overlie the inside face thereof, said main bellows section presenting an outer part extending from the end of the enclosing panel section to the plane of the erected end wall panel and an inner section extending inwardly beyond the plane of the erected end wall panel, said complementary bellows section being hinged to the inner end of said main bellows section and to the adjacent side edge of the end wall panel and adapted to overlie only the inner part of said main bellows section when the end wall panel is in erect position.

4. An improved carton having a bottom wall panel, a front enclosing panel and rear enclosing panel hinged to the opposite side edges of said bottom wall panel, an end wall panel set between said front and rear enclosing panels and hingedly connected along the bottom edge thereof to a spacer section overlying the inside face of the bottom wall panel and bellows fold portions overlying the inside face of each of said front and rear enclosing panels and connecting the adjacent ends of said front and rear enclosing panels to the adjacent vertical edges of said end wall panels, each of said bellows fold portions comprising a main bellows section and a complementary bellows section, each of said main bellows sections being hinged to the adjacent end of the adjacent enclosing panel and adapted to overlie the inside face thereof, said main bellows section presenting an outer part extending from the end of the enclosing panel section to the plane of the erected end wall panel and an inner section extending inwardly beyond the plane of the erected end wall panel, said complementary bellows section being hinged to the inner end of said main bellows section and to the adjacent side edge of the end wall panel and adapted to overlie only the inner part of said main bellows section when the end wall panel is in erect position.

5. An improved carton formed from a single blank of paperboard material having a tubular body defined by a bottom wall panel, a front wall enclosing panel and rear wall enclosing panel hinged to the opposite side edges of said bottom wall panel, and a cover panel hinged to the upper edge of said rear wall panel, a pair of end wall panels set within said tubular body and hinged to connect along the bottom edge thereof to a spacer section overlying the inside face of the bottom wall panel, and bellows fold portions overlying the inside face of each of said front and rear wall enclosing panels and connecting the adjacent ends of said front and rear wall enclosing panels to the adjacent vertical edges of said end wall panels, each of said bellows fold portions comprising a main bellows section and a complementary bellows section, each of said main bellows sections being hinged to the adjacent end of the adjacent enclosing panel and adapted to overlie the inside face thereof, said complementary bellows section being hinged to the inner end of said main bellows section and to the adjacent side edge of the end wall panel and adapted to overlie only a part of said main bellows section when the end wall panel is in erect position.

6. An improved carton formed from a single blank of paperboard material having a tubular body, a bottom wall panel, a front wall enclosing panel and rear wall enclosing panel hinged to the opposite side edges of said bottom wall panel, and a cover panel hinged to the upper edge of said rear wall enclosing panel, a pair of end wall panels

set within said tubular body and hinged connected along the bottom edge thereof to a spacer section overlying the inside face of the bottom wall panel, bellows fold portions overlying the inside face of each of said front and rear wall enclosing panels and connecting the adjacent ends of said front and rear wall enclosing panels to the adjacent vertical edges of said end wall panels, and a bracer flap hinged to and extending outwardly from each of said end wall panels, each of said bellows fold portions comprising a main bellows section and a complementary bellows section, each of said main bellows section being hinged to the adjacent end of the adjacent enclosing panel and adapted to overlie the inside face thereof, said complementary bellows section being hinged to the inner end of said main bellows section and to the adjacent side edge of the end wall panel and adapted to overlie only a part of said main bellows section when the end wall panel is in erect position.

7. An improved carton formed from a single blank of paperboard material comprising four hingedly connected enclosing panels forming a tubular body, a pair of spaced end wall panels set within said tubular body having means for suspending a merchandise article therebetween, and bellows fold portions hingedly connecting opposite side edges of each of said end wall panels to the adjacent ends of the adjacent enclosing panels, each of said bellows fold portions comprising a main bellows section and a complementary bellows section, each of said main bellows sections being hinged to the adjacent end of the adjacent enclosing panel and adapted to overlie the inside face thereof, said complementary bellows section being hinged to the inner end of said main bellows section and to the adjacent side edge of the end wall panel and adapted to overlie only a part of said main bellows section when the end wall panel is in erect position.

panel is in erect position.

8. An improved carton formed from a single blank of paperboard material comprising four hingedly connected enclosing panels forming a tubular body, a pair of spaced end wall panels set within said tubular body, means associated with said end wall panels for suspending a merchandise article therebetween, and bellows fold portions hingedly connecting opposite side edges of each of said end wall panels to the adjacent ends of the adjacent enclosing panels, said bellows fold sections providing a support fixedly maintaining said end wall panels in assembled position within said tubular body, each of said bellows fold portions comprising a main bellows section and a complementary bellows section, each of said main bellows sections being hinged to the adjacent end of the adjacent enclosing panel and adapted to overlie the inside face thereof, said complementary bellows section being hinged to the inner end of said main bellows section and to the adjacent side edge of the end wall panel and adapted to overlie only a part of said main bellows section when the end wall panel is in erect position.

9. An improved cartoon folder formed from a single blank of paperboard material comprising four hingedly connected enclosing panels forming a tubular body, a pair of spaced end wall panels set within said tubular body, means associated with said end wall panels for suspending a merchandise article therebetween, bellows fold portions hingedly connecting opposite side edges of each of said end wall panels to the adjacent ends 70 of the adjacent closing panels, and flaps hinged

to the other opposite edges of each of said end wall panels fixedly maintaining said end wall panels in assembled position within said tubular body, each of said bellows fold portions comprising a main bellows section and a complementary bellows section, each of said main bellows sections being hinged to the adjacent end of the adjacent enclosing panel and adapted to overlie the inside face thereof, said complementary bellows section being hinged to the inner end of said main bellows section and to the adjacent side edge of the end wall panel and adapted to overlie only a part of said main bellows section when the end wall panel is in erect position.

10. An improved carton folder formed from a single blank of paperboard material comprising, enclosing side panels forming a tubular body, a pair of spaced end wall panels set within said tubular body, bellows fold portions hingedly connecting opposite side edges of each of said end wall panels to the adjacent ends of the adjacent enclosing panel, a bracer flap hinged to each of said end wall panels along the upper end thereof, and a pair of locking ears hinged to each of said bracer flaps adapted to interlock with said adjacent bellows fold portions to retain the adjacent side wall panels of the carton in fixed assembled position.

11. An improved carton folder formed from a single blank of paperboard material comprising, a bottom wall panel and front and rear wall panels hinged to said bottom wall panel, a pair of inset end wall panels each hingedly connected by a spacer section to the adjacent end of said bottom wall panel, a bellows fold portion hingedly connecting opposite side edges of each of said end wall panels to the adjacent ends of said front and rear wall enclosing panels, and a tuck-in element extending from said rear wall panel adapted to be inserted between the inside face of said front wall enclosing panel and the adjacent bellows portions for retaining said carton in assembled form, each of said bellows fold portions comprising a main bellows section and a complementary bellows section, each of said main bellows sections being hinged to the adjacent end of the adjacent enclosing panel and adapted to overlie the inside face thereof, said complementary bellows section being hinged to the inner end of said main bellows section and to the adjacent side edge of the end wall panel and adapted to overlie only a part of said main bellows section when the end wall panel is in erect position.

12. An improved carton folder formed from a single blank of paperboard material comprising, a bottom wall panel and front and rear wall enclosing panels hinged to said bottom wall panel, a pair of inset end wall panels each hingedly connected by a spacer section to the adjacent end of said bottom wall panel, a bellows fold portion hingedly connecting opposite side edges of each of said end wall panels to the adjacent end of said front and rear wall panel, and a tuck-in flap hinged to said rear wall panel adapted to be inserted between the inside face of said front wall panel and the adjacent bellows portions for retaining said carton in assembled form, each of said bellows fold portions comprising a main bellows section and a complementary bellows section, each of said main bellows sections being hinged to the adjacent end of the adjacent enclosing panel and adapted to overlie the inside face thereof, said complementary bellows section being hinged to the inner end of said main bellows section and to the adjacent side edge of the end wall panel and adapted to overlie only a part of said main bellows section when the end wall panel is in erect position.

section and to the adjacent side edge of the end wall panel and adapted to overlie only a part of said main bellows section when the end wall panel is in erect position.

13. An improved carton formed from a single blank of paperboard material comprising, a bottom wall panel and front and rear wall enclosing panels hinged to said bottom wall panel along opposite side edges thereof, a pair of inset triangular shaped end wall panels, a bellows fold portion hingedly connecting opposite side edges of each of said end wall panels to the adjacent ends of said front and rear wall enclosing panels, and a tuck-in flap extending from said rear wall enclosing panel adapted to be inserted between the inside face of said front wall enclosing panel and the adjacent bellows fold portions for retaining said carton in assembled form, each of said bellows fold portions comprising a main bellows section and a complementary bellows section, each of said main bellows sections being hinged to the adjacent end of the adjacent enclosing panel and adapted to overlie the inside face thereof, said complementary bellows section being hinged to the inner end of said main bellows section and to the adjacent side edge of the end wall panel and adapted to overlie only a part of said main bellows section when the end wall panel is in erect position.

14. An improved carton formed from a single blank of paperboard material comprising, a bottom wall panel and front and rear wall enclosing panels hinged to said bottom wall panel along opposite side edges thereof, a pair of inset triangular shaped end wall panels, a spacer section overlying the bottom wall panel and connecting the adjacent end of the bottom wall panel to the adjacent end wall panel, a bellows fold portion hingedly connecting opposite side edges of each of said end wall panels to the adjacent ends of said front and rear wall enclosing panels, and a tuck-in flap extending from said rear wall enclosing panel adapted to be inserted between the inside face of said front wall enclosing panel and the adjacent bellows fold portions for retaining said carton in assembled form, each of said bellows fold portions comprising a main bellows section and a complementary bellows section, each of said main bellows sections being hinged to the adjacent end of the adjacent enclosing panel and adapted to overlie the inside face thereof, said complementary bellows section being hinged to the inner end of said main bellows section and to the adjacent side edge of the end wall panel and adapted to overlie only a part of said main bellows section when the end wall panel is in erect position.

RAYMOND E. FINK.
